PREFABRICATED SHINGLE CORNER UNIT

Filed Dec. 31, 1937

UNITED STATES PATENT OFFICE

2,113,303

PREFABRICATED SHINGLE CORNER UNIT

Alexis Kiefer, Detroit, Mich.

Application December 31, 1937, Serial No. 182,718

4 Claims. (Cl. 26—5)

This invention relates to pre-fabricated shingle corner units particularly adapted to be used with building covering units of the type generally designated as "strip shingles."

5 Strip shingles are ordinarily manufactured by coating a base of waterproof roofing felt or similar material with asphalt or the like, then applying a surface coating of grits, mica, sand or other mineral substance over the asphalt coating and 10 finally pressing the said mineral surface coating lightly into bonded relationship with the said asphalt coating.

15 Strip shingles having materially greater horizontal than vertical dimensions are generally adapted to simulate brickwork by providing the lower portion of the strip shingle with a surface coating of light colored granules or grits which imitate bricks and by vertically notching the said lower portion thereof to provide lateral spacing 20 of the said imitation bricks.

25 The upper portion of the strip shingles is generally dark in color and serves to simulate horizontal brick joints when the shingles are vertically overlapped so as to expose a narrow strip of the said dark upper portion of the next lower shingle below the lower edge of each strip shingle. The vertical notches in the lower portion of the said strip shingles serve to expose the dark upper portion of the next lower shingle at 30 the said vertical notches whereby to bring out a simulation of vertical mortar joints, the said strip shingles producing the effect of a neatly laid up brick wall when secured to a building surface in vertical overlapped and laterally staggered relationship.

35 In order to accomplish the proper simulation of brickwork at the corner of a rectangular structure where the wall on one side of a structure joins the wall of another side of a structure, one 40 side wall should end up at the corner with the side portion of a brick, and the adjacent side wall at the same course should expose the end portion of the same brick. The foregoing is very difficult to accomplish in walls covered with strip 45 shingles because, inasmuch as strip shingles are generally tapered downwardly outward with respect to a wall covered thereby and inasmuch as courses of strip shingles vertically overlap each other, the said strip shingles will lie in planes 50 at downwardly outward angles with respect to a wall covered thereby. As strip shingles are bent around corners of structures the inclination or sloping downwardly and outwardly thereof with respect to the wall covered thereby causes 55 the said shingles to twist downwardly out of

line with adjacent strips which are not bent around the said corners. Starting at the bottom of a wall at a corner when successive shingles are placed around the corner over each other in vertical overlapped relationship, the sloping of the said shingles at the corner downwardly and outwardly increases as successive courses of corner shingles are placed in vertical overlapping relationship to the shingles therebelow. Therefore, it has been found extremely difficult and 10 unsatisfactory to place strip shingles in vertical overlapping relationship to each other around the corner of a structure inasmuch as undesirable bulging of the outer surface of the corner results and inasmuch as the lower edges of shingles bent around the corner slope downwardly from the corner out of line with adjacent strip shingles.

20 With the foregoing in view, one object of my invention is to provide an improved corner unit 20 for strip shingle construction in which brickwork is simulated adapted to be easily and readily erected and which assures perfect alignment of the horizontal corner mortar joints with the horizontal mortar joints of strip shingle siding adjacent thereto.

25 Another object of the invention is to provide a rigid corner unit for strip shingle construction of the type described which may be readily and accurately applied by unskilled workmen.

30 Another object of the invention is to provide a pre-fabricated shingle corner unit for use with flexible strip shingles which positively eliminates bulging and misalignment of shingles at the corner of a structure covered therewith.

35 Another object of the invention is to provide a pre-fabricated shingle corner unit adapted to establish the vertical overlap and lateral position of strip shingles adjacent thereto and at the same time provide a perfect simulation of brickwork 40 at the corners of a structure covered with strip shingles.

45 A further object of my invention is to provide a pre-fabricated shingle corner unit for use with strip shingles rigidly reinforced to withstand handling and abuse during shipping and erection.

50 Other objects of the invention will become apparent by reference to the following detailed description taken in connection with the accompanying drawing, in which:

55 Fig. 1 is a view in perspective of pre-fabricated shingle corner units embodying the invention showing how the said units are erected in overlapped relationship and how the adjacent strip

shingles are placed in perfect alignment therewith.

Fig. 2 is a view in perspective of a three course high pre-fabricated shingle corner unit embodying the invention.

Fig. 3 is a view in perspective showing a one course high pre-fabricated shingle corner unit embodying the invention.

Fig. 4 is a vertical sectional view taken on the line 4-4 of Fig. 1.

Fig. 5 is a greatly enlarged vertical sectional view taken on the line 5-5 of Fig. 1.

Fig. 6 is a vertical sectional view taken on the line 6-6 of Fig. 3.

Referring now to the drawing wherein like numerals refer to like and corresponding parts throughout the several views, Figs. 1 and 4 show typical pre-fabricated shingle corner construction embodying the invention composed of a one course high pre-fabricated shingle unit A with a three course high pre-fabricated shingle unit B erected in vertical overlapped relationship thereover. The usual overlapped strip shingle wall covering is indicated in Fig. 1 in laterally juxtaposed position to the pre-fabricated shingle corner units A and B shown therein. The one course high pre-fabricated shingle corner unit A disclosed in Figs. 3 and 6 is composed of a brick simulating type strip shingle 10 having the upper portion 11 thereof preferably dark colored and the lower portion 12 thereof surface coated with a contrasting color of granules or grits of such a nature as to simulate brick. The said strip shingle 10 of the corner unit A is bent at the desired angle, for example 90 degrees, and is backed up at the said bend with a similarly bent reinforcing plate 13 preferably of metal or like substantially rigid reinforcement material which will maintain the shingle corner unit A at the angle to which the said strip shingle 10 is bent.

For convenience, the upper dark portion of the brick simulating type shingles is shown stippled throughout the drawing and the lower surface coated portion of the said brick simulating type shingles is shown shaded with vertical shade lines throughout the drawing.

Before bending the said strip shingle 10 of the shingle corner unit A and backing the same up with the reinforcing plate 13, approximately one-half of the dark-colored upper portion 11 of the said strip shingle 10 is cut away substantially as indicated in Fig. 3 leaving a narrow strip 14 of the said dark colored upper portion 11 adjacent the lower surface coated portion 12 which serves to simulate a horizontal mortar joint when the surface coated portion of another corner unit is juxtaposed in butted relationship thereto.

The reinforcing plate 13 is preferably secured to the back of the bent strip shingle 10 shown in Fig. 3 by such suitable means as hot asphalt or other cementitious material 18. The said reinforcing plate 13 is vertically offset with respect to the said bent strip shingle 10 so as to admit of the vertical overlapping of the said bent strip shingle 10 with the reinforcing plate projecting above the next lower corner shingle unit, to provide a butt joint between the bent strip shingles of vertically adjacent pre-fabricated shingle corner units and to provide a butt joint between the reinforcing plates of vertically adjacent pre-fabricated shingle corner units.

The embodiment of the shingle corner unit A shown in Fig. 3 is right hand. It is obvious that like left hand shingle corner units must be alternated with right hand shingle corner units when

erecting the same to admit of erecting the said shingle corner units with the lower surface coated portion of one shingle corner unit in vertical overlapping relationship with the upwardly projecting end of the reinforcing plate of the next lower shingle corner unit.

Fig. 2 shows a left hand three course high pre-fabricated shingle corner unit B which is constructed substantially like the said shingle corner unit A previously described except that it is composed of a single three course high reinforcing plate 130, one vertically central bent right hand strip shingle 10 which has a dark colored upper portion 11 and a brick simulating lower portion 12 and one top and one bottom bent left hand strip shingle 100 which have dark colored upper portions 110 and brick simulating lower portions 120. The lower bent portions 12 and 120 of the said bent strip shingles 10 and 100 are connected to the said three course high reinforcing plate 130 with the said reinforcing plate 130 projecting a short distance above the top bent left hand strip shingle 100 and with the bottom bent left hand strip shingle 100 extending a like distance below the said reinforcing plate 130. The lower bent corner portions of the said top left hand shingle 100, the said central right hand shingle 10 and the bottom left hand shingle 100 are all disposed in a vertical plane and in butt joint relationship with each other against the corner of the said reinforcing plate 130.

It is obvious that the lower portions 12 and 120 of the strip shingles 10 and 100 respectively are slightly separated from the reinforcing plates 13 and 130 respectively when they laterally overlap the upper portion 11 or 110 of the next lower course of bent strip shingles 10 or 100 as the case may be, which separation is accomplished during manufacture or erection of the said shingle corner units as required.

The lateral ends of strip shingles 10 and 100 are suitably notched at 15 and 150 respectively to cooperate with similar notches 16 at the ends of the lower brick simulating portion of the horizontally staggered and vertically overlapping brick simulating strip shingles 17 shown in dot and dash lines in Fig. 1.

By first nailing the one course high corner shingle unit A to the lowest portion of the corner of a structure to be cornered with strip shingles, and then securing the three course high shingle corner unit B in butt joint relationship with the top said shingle corner unit A which automatically places the lower strip shingle 100 of the said corner shingle unit B in vertical overlapping relationship with respect to the reinforcing plate 13 of the said corner shingle unit A, the corner shingle construction disclosed in Fig. 1 is accomplished in which the shingles at the completed corner are positioned in perfect vertical alignment, in which the horizontal brick joints are maintained perfectly horizontal and which establishes the proper horizontal staggered and vertical overlapped relation of the adjacent strip shingles 17 thereby assuring a perfect simulation of brickwork with comparatively unskilled workmen as erectors.

Although but one embodiment of the invention has been disclosed herein in one and three course high right hand and left hand units, it is obvious that the invention may be practiced in any desired number of course units and in both right hand and left hand forms, and that many changes in the size, shape, arrangement and detail of the various parts thereof may be made without de-

parting from the spirit of the invention as defined in the appended claims.

I claim:

1. A pre-fabricated shingle corner unit comprising a strip shingle having one upper corner thereof cut away leaving one low side thereof of a height equivalent to the portion of the said strip shingle normally exposed to the weather after erection, the said low side of the strip shingle being bent in a vertical plane to a desired corner angle, and a reinforcing plate of equal height to the bent low side of the said strip shingle bent to a like corner angle secured to the rear of the said strip shingle with the corner bend thereof in registry with the corner bend of the said strip shingle, the said reinforcing plate being vertically offset with respect to the low side of the said strip shingle whereby to admit of vertically staggered butt joints between the strip shingles and the reinforcing corner plates of like shingle corner units when the said shingle corner units are vertically juxtaposed with the strip shingle of one shingle corner unit in vertical overlapping relationship with respect to the reinforcing plate of the next subjacent shingle corner unit.

2. A pre-fabricated shingle corner unit comprising a plurality of strip shingles each having one upper corner thereof cut away leaving one lower side thereof of a height equivalent to the portion of the said strip shingle normally exposed to the weather after erection, the said low side of each of the said strip shingles being bent in a vertical plane to a desired corner angle, and a reinforcing plate of a height equal to the total height of the low sides of all the strip shingles bent to a like corner angle secured to the rear of the said strip shingles with the corners of said strip shingles in abutting relationship with respect to each other and with the corner bend of the said reinforcing plate in registry with the corner bends of the said strip shingles, the said reinforcing plate being vertically offset with respect to the abutted low sides of the said strip shingles whereby to admit of vertically staggered butt joints between the strip shingles and reinforcing corner plates of like shingle corner units when the said shingle corner units are vertically juxtaposed with the lower strip shingle of one shingle corner unit in vertical overlapping relationship with respect to the reinforcing plate of the next subjacent shingle corner unit.

3. A pre-fabricated shingle corner unit comprising a strip shingle composed of upper and lower portions of contrasting color, the said lower portion simulating brick, one upper corner of the upper portion of the said strip shingle being cut away in such a manner as to leave a narrow strip of the said upper portion vertically adjacent the brick simulating lower portion which serves to simulate a horizontal mortar joint when the lower

portion of another shingle corner unit is juxtaposed thereabove, the brick simulating lower portion of the said strip shingle including the narrow mortar joint simulating strip of the upper portion vertically adjacent thereto being bent in a vertical plane to a desired corner angle, and a reinforcing plate of a height equal to the combined height of the brick simulating lower portion and the mortar joint simulating strip bent to a like corner angle secured to the rear of the said strip shingle with the corner bend thereof in registry with the corner bend of the said strip shingle and with the bottom thereof positioned above the bottom of the said strip shingle and with the top thereof extending above the narrow horizontal mortar joint simulating strip of the said strip shingle whereby to admit of vertically staggered butt joints between the strip shingles and reinforcing corner plates of like shingle corner units when the said shingle corner units are vertically juxtaposed with the lower strip shingle of one shingle corner unit in vertical overlapping relationship with respect to the reinforcing plate of the next subjacent shingle corner unit.

4. A pre-fabricated shingle corner unit comprising a plurality of strip shingles each composed of upper and lower portions of contrasting color, the lower portion of each strip shingle simulating brick, one upper corner of the upper portion of each strip shingle being cut away in such a manner as to leave a narrow strip of the said upper portion of each strip shingle vertically adjacent the brick simulating lower portion thereof which serves to simulate a horizontal mortar joint when the lower portion of another shingle corner unit or another strip shingle is juxtaposed thereabove, the low side of each strip shingle composed of the brick simulating lower portion and the narrow mortar joint simulating strip of the upper portion vertically adjacent thereto being bent in a vertical plane to a desired corner angle, and a reinforcing plate of a height equal to the total height of the low sides of all the strip shingles bent to a like corner angle secured to the rear of the said strip shingles with the corners of the said strip shingles in abutting relationship with respect to each other and with the corner bend of the said reinforcing plate in registry with the corner bends of the said strip shingles, the said reinforcing plate being vertically offset with respect to the abutted low sides of the said strip shingles whereby to admit of vertically staggered butt joints between the strip shingles and reinforcing corner plates of like shingle corner units when the said shingle corner units are vertically juxtaposed with the lower strip shingle of one shingle corner unit in vertical overlapping relationship with respect to the reinforcing plate of the next subjacent shingle corner unit.

ALEXIS KIEFER.
